TUBE MAKING APPARATUS

August P. Diescher, Pittsburgh, Pa., assignor to
 Diescher Tube Mills, Inc., Pittsburgh, Pa., a
 corporation of Delaware

Application May 2, 1936, Serial No. 77,523

2 Claims. (Cl. 80—54)

The invention relates to cross-rolling mills for helically acting upon seamless tubular blanks, particularly of steel or other ferrous base metals, and contemplates various types of such mills such as those used for reducing the wall thickness of and elongating tubular blanks, those used for reducing the diameter of tubes, usually designated as sink mills, and those used for expanding tubular blanks either with or without some elongation of them.

As heretofore used in actual practice, such cross-rolling mills have been constructed and operated as single units with a separate drive for each. It is sometimes desirable to give tubular blanks or tubes two or more passes through cross-rolling mills, and in doing this it is desirable to avoid intermediate heating such as would be necessary if a material amount of time were required to convey blanks from one to another pass, whether the second pass be through the same or through another mill. In the straight rolling of metal, as for example strip metal, it is possible to position a plurality of roll stands so close to each other that the metal is simultaneously in the passes of a plurality of rolls, but, due to the peculiar flow of metal in cross-rolling operations, it is impractical, if not impossible, to so position cross-rolling mills that a tubular blank is simultaneously in two passes.

The object of this invention is to provide a tandem cross-rolling mill for the purpose explained which is economical to build as well as to operate, the mill being equipped with a drive which simplifies the construction and operation of the mill and which facilitates rapid handling of blanks between passes.

The invention is somewhat diagrammatically illustrated in the accompanying drawing, of which Fig. 1 is a plan view of a tandem cross-rolling mill and drive for it; Fig. 2 an elevation to enlarged scale of the drive shown in the central portion of Fig. 1, some parts being shown in section; and Fig. 3 a side view of the drive shown in Fig. 2, the plane of view being indicated by the line III—III, Fig. 2.

In the practice of this invention a pair of cross-rolling mills are arranged in tandem for successive action upon tubular blanks. These mills may be any of the several types explained above for reducing, elongating, expanding and sinking seamless blanks or tubes. Each mill is provided with a plurality of, preferably two, cross-rolls which may be of any well-known or desired construction, as for example barrel-shape, conical or overlapping disc rolls. Between the two mills

there is a power unit with connections extending from it to each mill for properly driving their cross-rolls. In the illustrative embodiment of the invention, it is shown in its applicability to a tandem mill for reducing the wall thickness of and elongating tubular blanks upon cylindrical mandrels which pass through the mills within the blanks. When it is desired to produce tubing having unusually thin walls it is advantageous to effect the necessary reduction and elongation in a plurality of passes. Also, in the sinking of tubes to reduce their diameters substantial amounts it is desirable to give the tubes a plurality of passes.

Having reference to the embodiment of the invention illustrated in the drawing, a pair of cross-rolling mills 1 and 2 are shown in tandem, each being the same except for the right and left-hand arrangements of their drives. Each includes a pair of barrel-shape cross-rolls 3 having a pair of driven guide discs 4 arranged between them, one above and one below the line of pass through the mill. The construction and manner of operating such mills when used for elongating tubular blanks is disclosed in Patent No. 1,870,209, and the method of operating such mills for sinking tubes is disclosed in Patent No. 1,934,844, both to Samuel E. Diescher. It will be understood, however, that the invention contemplates types of cross-rolling mills other than those here illustrated and than those disclosed in these patents. The guide discs 4 of each mill are driven at a relatively high peripheral speed through suitable spindles 5 which connect them to driving motors.

Arranged between the two mills there is a single power unit, which, in the illustrated embodiment of the invention, consists of a gear box 6 equipped with suitable gears adapted to be driven by a motor 7. To drive the cross-rolls with a minimum loss of power the gear box preferably extends directly across the line of pass between the mills, and is provided substantially centrally of its upper portion with an opening 8 equipped with a tubular guide 9 through which the blanks or tubes pass from one to the other of the mills. Grouped around opening 8 there are gears 10, 11, 12 and 13 connected, respectively, to coupling heads 14, 15, 16 and 17. The gears 10 and 11 are both driven by a single gear 18, which, through gears 19 and 20 and a pinion 21, is driven by motor 7. The gear 12 is driven by gear 11 through an idler gear 22, and similarly the gear 13 is driven by gear 10 through an idler gear 23. The several

arrows on these gears indicate their direction of rotation to properly drive spindles 24, 25, 26 and 27 connected, respectively, to the coupling heads 14, 16, 15 and 17. The spindles 24 and 25 drive the cross-rolls 3 of mill 1, and the spindles 26 and 27 similarly drive the cross-rolls 3 of mill 2.

Arranged between mill 1 and gear box 6 there is a roller table or conveyor 28 which may be of conventional or any desired form driven by a motor 29 through the connections indicated in Fig. 1, and similarly between gear box 6 and mill 2 there is a roller table or conveyor 30 adapted to be driven by a motor 31.

In the operation of the tandem mill when used to elongate and reduce the wall thickness of tubular blanks, a cylindrical mandrel is placed within a blank before the blank is passed through mill 1. In Fig. 2 there is shown the forward end of a blank 32 containing a cylindrical mandrel 33 after such end has passed through mill 1 and is about to enter guide 9 arranged in the opening 8 of the gear box. The spacing of the two mills is such that a blank passes completely through mill 1 before it enters mill 2, to the latter of which it is conveyed by roller tables 28 and 30. However, the mills are sufficiently close to each other that the forward end of the blank enters mill 2 shortly after its rear end passes beyond mill 1. Thus there is no unnecessary delay between passes, and accordingly intermediate heating of blanks is unnecessary. By driving the two mills with a single power unit in the manner shown and described the mills may be placed sufficiently close to each other to accomplish these advantages, and there also results a material saving in the initial cost of equipment and in the cost of op-

erating the mill. By using tandem cross-rolling mills of the particular type herein disclosed, that is to say mills equipped with driven guide discs, very thin-walled tubing can be produced in two passes without subjecting the guide discs to excessive wear.

According to the provisions of the patent statutes, I have explained the principle and mode of operation of my invention and have illustrated what I now consider to represent its best embodiment. However, I desire to have it understood that, within the scope of the appended claims, the invention may be practiced otherwise than as specifically illustrated and described.

I claim as my invention:

1. A mill for acting upon tubular blanks, comprising a pair of cross-rolling mills arranged in tandem for successive action upon tubular blanks, each mill including helically acting cross-rolls, a gear box positioned between said mills and across the line of pass through them, and driving spindles extending from the gears in said box to the cross-rolls of each of the said mills.

2. A mill for acting upon tubular blanks, comprising a pair of cross-rolling mills arranged in tandem for successive action upon tubular blanks, each mill including helically acting cross-rolls, a gear box positioned between said mills and across the line of pass between them and provided with an opening through it for the passage of blanks from one to the other of the mills, and driving spindles extending from the gears in said box to the cross-rolls of each of said mills.

AUGUST P. DIESCHER.
